(57) **CLAIM**

The ornamental design for a front door panel for a motor vehicle, as shown and described.

DESCRIPTION

FIG. 1 is a front perspective view of a first embodiment of a front door panel for a motor vehicle showing our new design; FIG. 2 is a front view thereof; FIG. 3 is rear view thereof; FIG. 4 is a left side view thereof; FIG. 5 is a right side view thereof; FIG. 6 is a top plan view thereof; and, FIG. 7 is a bottom view.

Our design includes a second embodiment of a front door panel for a motor vehicle that is a mirror image of the design shown in FIGS. 1-7.
